UNITED STATES PATENT OFFICE.

HEINRICH W. WAGENER, OF MOSCOW, RUSSIA.

STEAM-BOILER.

No. 821,558.

Specification of Letters Patent.

Patented May 22, 1906.

Application filed February 27, 1906. Serial No. 303,242.

To all whom it may concern.

Be it known that I, HEINRICH W. WAGENER, manufacturer, a subject of the Russian Emperor, residing at Moscow, in the Empire of Russia, have invented certain new and useful Improvements in Steam-Boilers, of which the following is a full, clear, and exact description.

The present invention relates to improvements in that class of steam-boilers in which the latter consist of a system of water-tubes above which a receiver for steam and water is provided. In these boilers the ends of the water-tubes are connected to water-chambers, and the whole system of tubes forms a Latin U, carrying the fire-grate or other means for the production of the necessary heat between its shanks. At present the arrangement of these boilers is such that the hot gases 20 pass over the fire-bridge, through the spaces between the tubes, and then downward into a flue provided below the system of tubes. A disadvantage of these boilers consists in the fact that of those portions of the tubes which 25 lie above the fire-grate only a small surface is subjected to the influence of the hot gases, because the current of them is directed diagonally over the fire-bridge.

The object of the present invention is to 30 avoid this disadvantage by providing a body of brickwork immediately above the uppermost row of the tubes, and that in such a manner that one part of the gases rising from the fire-grate is caused to pass over the fire-bridge and through the spaces between the tubes, while the other part is to take its way 35 vertically through the spaces between the tubes and thereafter through an opening left between the front wall of the boiler-brick-work and the brickwork body. The gases pass then horizontally through a space left 40 between the said brickwork body and the steam-reservoir and turn finally downward through a second opening provided at the rear end of the brickwork body. The gases 45 having thus passed over the brickwork body are then mixed with other gases coming from the fire-bridge and turning downward, and the whole mass of gases will then heat the remaining portions of the water-tubes, as usual.

In the annexed drawings two kinds of construction of the present improved steam-boiler are illustrated.

Figure 1 is a vertical longitudinal section

of the one construction, and Fig. 2 a similar section of the modified form.

In Fig. 1 the water-tubes *a* are arranged to form a Latin U, and these tubes connect two water-chambers *b* and *c*, suitably supported by the brickwork of the boiler. A connection *d* serves to lead the mixture of steam and water entering the upper chamber into the reservoir *e*, which is connected to the lower chamber *c* by means of outer tubes *f*. The fire-grate *g*, bridge *h*, and ash-pit *i* are arranged between the shanks of the system of tubes *a*, as shown. Immediately above the upper shank of the system of tubes a body *k* of fireproof material (e. g., fireproof brick-work) is provided, and between this body and the receiver *e* remains a channel *l*, which the fire-gases enter through the opening *m* and leave through another opening *n*. As indicated by the arrows, one part of the gases rising from the grate *g* passes immediately over the fire-bridge *h* into the back chamber *o*, while the other part rises vertically through the system of tubes and the opening *m*. These latter gases then pass through the channel *l* and opening *n*, whereupon they are 80 mixed with other gases entering the chamber *o* from the fire-bridge. The whole of the gases thus mixed now passes along the outer surface of the tubes *a* and into a flue *p*, which leads them to the chimney. In order to support the curved part of the system of tubes, the feet *q* are provided resting with their lower curved ends on iron plates embedded into the basement of the boiler, and the outer row of tubes rests on the upper ends of these feet. 90 In order to support also the inner tubes, the pieces *r* are inserted.

In the modified form of the boiler shown by Fig. 2 a third water-chamber *s* is provided, and the tubes, which in this instance are 95 straight, form two separate systems. The necessary heat is produced by means of oil. The required apparatuses for feeding this fuel are not shown. It may be remarked that a superheater for steam can be located within 100 the channel *l*.

Having now described and ascertained the nature of my invention and in what manner the same is to be performed, what I claim is—

1. In a steam-boiler an arrangement of water-tubes similar to a Latin U, water-chambers connected by said tubes, a fire-bridge

and means for producing heat, both provided between the shanks of the system of tubes, a body of fireproof substance arranged to permit only one part of the hot gases produced 5 between the shanks of the water-tubes to pass over the fire-bridge, a branch channel provided above the said fireproof body, openings adapted to lead hot gases into and out of such branch channel, gas-passages adapted 10 to lead the hot gases along the tubes and to the chimney, substantially as set forth.

2. In a steam-boiler an arrangement of water-tubes similar to a Latin **U**, water-chambers connected by said tubes, a fire-bridge and means for producing heat, both provided 15 between the shanks of the system of tubes, a body of fireproof substance arranged to permit only one part of the hot gases produced between the shanks of the water-tubes to 20 pass over the fire-bridge, a branch channel provided above the said fireproof body, openings adapted to lead hot gases into and out of such branch channel, gas-passages adapted to lead the hot gases along the tubes and 25 to the chimney, a reservoir located above the fireproof body, and forming the upper limitation of the branch channel, substantially as set forth.

3. In a steam-boiler a system of water-30 tubes, each tube being bent into a shape similar to a Latin **U**, two water-chambers, connected by said tubes, a fire-bridge and means for producing heat both provided between the shanks of the system of tubes, a body of fire-35 proof substance arranged to permit only one part of the hot gases, produced between the shanks of the water-tubes, to pass over the fire-bridge, a branch channel provided above the said fireproof body, openings adapted to 40 lead hot gases into and out of such branch channel, gas-passages adapted to lead the hot gases along the tubes and to the chimney, substantially as set forth.

4. In a steam-boiler a system of water-45 tubes, each tube being bent into a shape similar to a Latin **U**, two water-chambers connected by said tubes, a fire-bridge and means for producing heat both provided between the shanks of the system of tubes, a body of fire-50 proof substance arranged to permit only one part of the hot gases produced between the shanks of the water-tubes to pass over the fire-bridge, a branch channel provided above the said fireproof body, openings adapted to 55 lead hot gases into and out of such branch channel, gas-passages adapted to lead the hot gases along the tubes and to the chimney, a reservoir located above the fireproof body, and forming the upper limitation of the 60 branch channel, substantially as set forth.

5. In a steam-boiler a system of water-tubes, each tube being bent into a shape similar to a Latin **U**, two water-chambers connected by said tubes, means for supporting the 65 curved portions of the tubes, a fire-bridge

and means for producing heat, both provided between the shanks of the system of tubes, a body of fireproof substance arranged to permit only one part of the hot gases, produced between the shanks of the water-tubes 70 to pass over the fire-bridge, a branch channel provided above the said fireproof body, openings adapted to lead hot gases into and out of such branch channel, gas-passages adapted to lead the hot gases along the tubes and 75 to the chimney, substantially as set forth.

6. In a steam-boiler a system of water-tubes, each tube being bent into a shape similar to a Latin **U**, two water-chambers connected by said tubes, means for supporting the 80 curved portions of the tubes, a fire-bridge and means for producing heat both provided between the shanks of the system of tubes, a body of fireproof substance arranged to permit only one part of the hot gases, produced 85 between the shanks of the water-tubes to pass over the fire-bridge, a branch channel provided above the said fireproof body, openings adapted to lead hot gases into and out of such branch channel, gas-passages adapted to lead the hot gases along the tubes and 90 to the chimney, a reservoir located above the fireproof body, and forming the upper limitation of the branch channel, substantially as set forth.

7. In a steam-boiler a system of water-tubes, each tube being bent into a shape similar to a Latin **U**, two water-chambers connected by said tubes, supporting-feet the upper 95 ends of which being in engagement with the outer row of tubes while the lower ones movably rest on the basement of the boiler, other supporting-pieces located between the inner 100 rows of tubes, a fire-bridge and means for producing heat both provided between the shanks of the system of tubes, a body of fire-105 proof substance arranged to permit only one part of the hot gases, produced between the shanks of the water-tubes, to pass over the fire-bridge, a branch channel provided above the 110 said fireproof body, openings adapted to lead hot gases into and out of such branch channel, gas-passages adapted to lead the hot gases along the tubes and to the chimney, substantially as set forth.

8. In a steam-boiler a system of water-tubes, each tube being bent into a shape similar to a Latin **U**, two water-chambers connected by said tubes, supporting-feet, the upper 115 ends of which being in engagement with the outer row of tubes while the lower ones movably rest on the basement of the boiler, other supporting-pieces located between the inner 120 rows of tubes, a fire-bridge and means for producing heat, both provided between the shanks of the system of tubes, a body of fire-125 proof substance arranged to permit only one part of the hot gases produced between the shanks of the water-tubes to pass over the fire-bridge, a branch channel provided above 130

the said fireproof body, openings adapted to lead hot gases into and out of such branch channel, gas-passages adapted to lead the hot gases along the tubes and to the chimney, a
5 reservoir located above the fireproof body, and forming the upper limitation of the branch channel, substantially as set forth.

In witness whereof I subscribe my signature in presence of two witnesses.

HEINRICH W. WAGENER.
